Lucille T. Facci, 119 Forest Road, Valley Stream, N.Y.

Filed Jan. 22, 1963, Ser. No. 73,271

Term of patent 14 years

(Cl. D57—1)

FIG. 1

FIG. 3

FIG. 1 is a front elevation view of a pair of louvered sun glasses illustrating my new design;

FIG. 2 is a sectional plan view thereof taken along line 2—2 of FIG. 1; and

FIG. 3 is a side elevation view thereof, the temple pieces being broken away for convenience of illustration.

The rear of the sun glasses frame, not shown, is plain and the temple, not shown, is like the temple shown, the external surfaces thereof being plain.

I claim:

The ornamental design for a pair of louvered sun glasses, substantially as shown and described.
